(57) **CLAIM**

The ornamental design for a plane, as shown and described.

DESCRIPTION

FIG. 1 is a perspective view from above and one side showing the plane with a blade cover in place;

FIG. 2 is a perspective view thereof from below and the other side;

FIG. 3 is a top plan view thereof;

FIG. 4 is an end view thereof from left to right as viewed in FIG. 3;

FIG. 5 is an end view thereof from right to left as viewed in FIG. 3;

FIG. 6 is a side view thereof;

FIG. 7 is an exploded view thereof;

FIG. 8 is a view from above and one side showing the blade cover removed and stored; and,

FIG. 9 is a view from underneath one side with the blade cover removed showing a first stage in rotating the bottom plate from a use position to a storage position.

The dashed lines in the drawings are directed to features of the plane that form no part of the claim.
